CALCULATING MACHINE

Walter J. Pasinski, Howell, Mich., assignor to
Burroughs Adding Machine Company, Detroit,
Mich., a corporation of Michigan

Application October 30, 1935, Serial No. 47,368

4 Claims. (Cl. 235—62)

This invention relates to a calculating machine. It is concerned particularly with an amount-key-responsive type of machine sometimes called an "automatic" calculator. Such a machine is disclosed in Pasinski No. 1,909,714 and the present invention is directed to improvements in this machine.

Machines of this type have heretofore been used mainly for performing addition. It has been possible to perform subtraction by depressing keys corresponding to the complement of the subtrahend, which resulted in performing subtraction by a process of complemental addition. However, the selection of keys corresponding to the complement of the subtrahend increases the work required of the operator and requires that two different digits be inscribed on the top of each key top. The present invention concerns an improvement in this type of calculator that enables the operator to enter the subtrahend in the same manner as if it were to be added and, then, by merely depressing a key to subtract said subtrahend.

Prior machines of this type have also had two registers with provisions for transferring the total from one register to the other, but this transfer operation has been limited to transferring totals in a positive direction. The present invention concerns an improvement whereby a total may be transferred either additively or subtractively from one register to the other.

The general object of the invention is, therefore, to provide an improved amount-key-responsive calculator.

A more particular object is to provide an amount-key-responsive calculator with an improved means for enabling subtraction to be performed.

A further object is to provide a key-responsive calculator with improved means for transferring a total from one register to the other either additively or subtractively.

It is also an object of this invention to provide suitable and necessary mechanisms whereby totals may be transferred subtractively in a key responsive calculator in which different columns of the machine may be selected as the units column.

Other objects and their resultant advantages will be apparent to those skilled in the art from the following description when read in connection with the drawings in which:

Fig. 1 is a right side elevation of a calculating machine embodying the principles of this invention, the cover and certain parts being removed

and broken away to show the novel features, all in normal position;

Fig. 2 is a right side elevation illustrating more particularly the operating or control keys all in normal position;

Fig. 2^a is a fragmentary detail of a portion of the clutch;

Fig. 3 is an enlarged right side elevation of the front portion of the machine illustrating a subtraction operation with the digit 3 in the front register and being transferred to the rear register as the true complement 7;

Fig. 4 is an enlarged side elevation of an index plate such as is used in all but the units column;

Fig. 5 is a view similar to Fig. 4 but illustrating an index plate used in the units column;

Fig. 6 is a fragmentary right side elevation illustrating certain conditions with the decimal transfer cut-out key depressed; and

Fig. 7 is an enlarged fragmentary detail of the index plate and associated parts used in the fourth column to transfer a true complement when the first three columns to the right thereof are blocked against transfers by depression of the decimal transfer cut-out key.

The invention is shown applied to the Burroughs automatic electric calculator which has been on the market for some time and which is disclosed in Pasinski No. 1,909,714. This machine will be described briefly, reference being made to said Pasinski patent for further details.

General features

The calculator has a plurality of banks of amount keys 10 (Fig. 1) whose stems are slidably mounted between upper and lower plates, 11 and 12, of a keyboard. The keys are urged upward by springs 13 but may be depressed downward to enter items. The key stems have lateral projections 14 that are located so that, when a key is depressed, its lug is positioned in the path of a projection 16 on an index bar 17 to limit the movement of the bar to a distance corresponding to the digital value of the key depressed. It will be understood that the bars 17 and have a plurality of projections 16 and that there is a bar for each bank of keys.

The lower end of each key stem is positioned to move into a slot 18 formed in a slide 19 which is urged forward by a spring 21, there being a slide 19 for each bank of keys. The arrangement is such that, when a key is depressed, it moves into its slot 18 and thereby moves the slide 19 rearward for the purpose of starting the motor. The slide 19 is temporarily latched

in rearward position by a latch 33 (Fig. 1) as described in said Pasinski patent and, when so latched, it holds the depressed key in depressed position.

The driving motor M is a normally inactive electric motor controlled by a switch 26 in the motor circuit. Normally, this switch is open, being held in open position by a bail 23 spring urged to the left in Fig. 1 by a spring 28. Each slide 19, which is moved to the rear whenever a key in its bank is depressed, has a downwardly projecting finger 22 (Fig. 1) positioned to engage the bail 23 so that, when any amount key is depressed in any bank, the motor switch 26 will be closed and the motor started.

The motor M drives a main shaft 29 through suitable gears, not shown, but disclosed in detail in said Pasinski patent. This shaft extends across the width of the machine and fixed to it is a series of toothed disks 31, there being a disk for each bank of the machine. When the motor is operated, these disks are rotated counter-clockwise as viewed in Fig. 1. The index bar 17 of each bank is connected to its toothed disk 31 by means of a pawl 32, which is carried by an arm 32a connected to the index bar 17, said arms being pivoted on shaft 29. The pawl 32 normally is held ineffective by a pivoted member 34 but, when the slide 19 of any bank is moved rearward, it rocks its member 34 counterclockwise which releases its pawl 32. Said pawl 32 then engages its toothed disk 31 and the disk moves the corresponding arm 32a counterclockwise to move the index bar 17 forward. The forward movement of index bar 17 continues until one of its projections 16 strikes the lug 14 on the depressed key. When this occurs a relative movement between the arm 32a and the index bar 17 takes place which rocks a member 35 that disengages the pawl 32 and releases the latch 33. Disengagement of pawl 32 releases the index bar 17 which is thereupon moved rearward to normal by its spring 36 (Fig. 1) connected to the lower end of its arm 32a. Release of latch 33 permits slide 19 to be returned forward to normal by its spring 21 which results in opening the motor circuit and releasing the depressed amount key.

The forward end of each index bar 17 is pivotally connected to a toothed actuator 40 pivoted at 41a. This actuator meshes with a gear 41 carrying a pawl 42 (Fig. 1). The pawl 42 is arranged so that when gear 41 is rotated clockwise, as it is by forward movement of the index bar 17, it slips over studs 43 on a gear 44 but, when the gear 41 is rotated counterclockwise by the return movement of index bar 17, said pawl engages one of said studs 43 and rotates the gear 44 counterclockwise. The gear 44 is in constant mesh with the pinions of the front registering mechanism.

The front registering mechanism, which is positioned at the front of the keyboard as shown in Fig. 1, comprises a series of register pinions 47, there being a pinion and set of gears 41-44 for each bank of the machine. These register pinions are visible through a sight opening 48 in the casing 49. A suitable tens-transfer mechanism is provided. For further details of the registering mechanism, reference is made to said Pasinski Patent No. 1,909,714 and to Gooch 1,128,679.

Upon depression of an amount key, the slide 19 in the bank in which the key is depressed is moved rearward to thereby start the motor which

immediately moves the corresponding index bar 17 forward to differential position. The index bar is then automatically disconnected and the motor switch is opened. No actuation of the register occurs during the forward movement of the index bar 17 but, upon the return movement of the bar, the corresponding register pinion 17 is moved in an additive direction an amount corresponding to the distance the index bar 10 was moved forward, which amount is, of course, determined by the digital value of the key depressed.

The above operation takes place almost instantly. When an operator depresses a key, the motor starts, the parts are connected and immediately operated, said parts are then disconnected, the motor stopped, and the amount registered in the pinion within a fraction of a second.

The front register may be cleared by depressing a clearing key FR (Fig. 2) which causes the motor to move a member 85a shown in dotted lines in Fig. 2 to thereby operate the clearing mechanism. It has not been considered necessary to illustrate and describe this mechanism in the present case, reference being made to British Patents Nos. 450,533 and 450,591 which disclose it in detail.

The above should be sufficient for a general understanding of the machine, reference being made to said Pasinski patent for further details.

Rear Registering Mechanism

Another registering mechanism is located at the rear of the keyboard, as shown in Fig. 1, which mechanism may be called the "rear" register or the "total-storing" register. In subtract operations, it may also be viewed as the "main" register.

This registering mechanism comprises a plurality of register pinions 51 and it is of exactly the same type as the front register heretofore described, being provided with suitable tens-transfer mechanism. It is indexed by actuators 53 pivoted at 54, said actuators engaging pinions 55 for driving the register pinions 51. The actuators 53 are indexed under control of mechanism governed by the front register, which mechanism will first be described in connection with transferring amounts from the front to the rear register additively.

Amount Transfers—Positive

Provision is made for quickly and easily transferring amounts from the front register, which may either be individual items or an accumulation of items, to the rear register by the mere depression of a single transfer key TR (Fig. 2). The mechanism for accomplishing this result additively is substantially that of my copending application Serial No. 694,550, filed October 21, 1933, disclosed in British Patents Nos. 450,533 and 450,591, and reference may be had to said patents for any details not described herein.

Each of the front register pinions 47 is provided with a small cam 61 (Fig. 1) having a uniform rise to correspond with the digital values of the pinion. A stud 62 on the upper end of a lever 64 pivoted at 65 is urged into engagement with the edge of this cam by a spring 66 that urges the lever 64 clockwise. When a register pinion is in "0" position as shown in Fig. 1, the stud 62 engages the low point of the snail cam 61. As the register pinion moves away from "0" the cam 61, engaging the stud 62, rocks the lever 64 counterclockwise about its pivot 65.

Pivots connected to the lower end of each lever 64 at 67 is a link 68 having an upwardly extending portion provided with a cam slot 69 best shown in Fig. 3. Positioned in the cam slot 69 is a stud 70 on an arm 71 forming a portion of a yoke 72, pivoted at 73 and urged counterclockwise (Fig. 3) by a spring 72^a. The yoke 72 has an extension 74 forming an index member or sector provided with two sets of stepped shoulders 75 and 76. For the present only the stepped shoulders 75 will be referred to in the description.

It is to be understood that there is an index member 74 with associated parts for each order of the machine and, from the above description it will be clear that these index members continuously reflect the amount in the front register; that is, at all times they are positioned in accordance with the positions of the snail cams on the pinions 47 of the front register.

Positioned for engagement with the stepped shoulders 75 in each order is a lug 77 formed on the forward end of a differential link or member 78 (Fig. 1) slidably supported at its front end on a stud 78^a. This link is somewhat irregularly shaped and extends rearward and upward to where it is pivotally connected at 79 (Fig. 1) to a downwardly extending lever 80 pivoted on the shaft 54. The upper end of the lever 80 is connected to the actuator 53 at 80^a and said lever 80 together with its actuator is urged counterclockwise in Fig. 1 by a spring 56, the lever 80 limiting against a bail 81 that engages the lower ends of the levers. The springs 56 thus urge the actuators 53 and levers 80 counterclockwise (Fig. 1) and, since the differential links 78 are connected to the lower ends of the levers 80, the links are urged rearward. However, normally, these parts cannot move because of the bail 81.

The bail 81 is moved rearward by the motor at the option of the operator and under the control of a transfer key TR (Fig. 2) to enable the differential links 78 to move to differential positions. Referring to Fig. 2, the bail 81 is carried by the lower ends of a pair of arms 81^a pivoted on the shaft 54 and urged counterclockwise by a spring 81^b. One of the arms 81^a carries a stud 81^c engaged by the slotted end of the upper arm of a bell crank 84 pivoted at 84^a. The lower arm of this bell crank carries a stud 84^b engaging the edge of a cam 83 that is connected through a clutch to the main drive shaft 29, which shaft, it will be recalled, is rotated counterclockwise in Fig. 2 when the motor operates. In the normal position of the parts, the stud 84^b contacts the high portion of the cam 83 and the bell crank 84 is held in the position of Fig. 2. When the cam 83 is rotated, the stud 84^b follows the cam edge under the urge of spring 81^b acting through parts 81^a, 81^c and 84 and, as the lower portion of the cam comes into position, the bail 81 is moved rearward, thereby releasing the actuators 53 and the links 78 for movement to differential positions by the springs 56 (Fig. 1). This movement of the actuators 53 does not enter an amount in the register pinions but, as the high point of cam 83 comes around to position, the bell crank 84 is rocked counterclockwise to move the bail 81 forward to normal and said bail moves the actuators clockwise to normal during which movement the indexed amount is entered in the register pinions 51 and the differential links 78 are returned forward to normal.

The transfer key TR is carried on a key stem 86 (Fig. 2) slidably mounted in the keyboard. Pivots connected at 100 to this key stem is one

arm of a bell crank 87 pivoted at 88 to a frame plate of the machine. The lower arm of this bell crank is connected to a link 89 that extends rearward where it is slidably supported on a stud 91, said link being urged rearward by a spring 90. The rear end of the link 89 has a lateral lug 92 normally extending over the end of the lower arm of the bell crank 84 to prevent movement of said bell crank unless the transfer key TR is depressed. Thus, even though the cam 83 may be rotated when the drive shaft rotates under control of the clearing keys described later, the bell crank 84 will not move unless the link 89 is moved forward by depression of the transfer key TR or the subtract key later described. When the transfer key TR is depressed, the bell crank 87 is rocked clockwise to move the link 89 forward to release the bell crank 84.

Depression of the transfer key TR also starts the motor and engages a clutch for rotating the cam 83. Referring again to Fig. 2, the stud 100 which connects the bell crank 87 to the stem 86 of the key TR, projects sufficiently to engage a cam slot 101 in a control slide 95 slidably mounted on studs 88 carried by one of the plates of the keyboard, said slide being urged rearward by a spring 88^a. The cam slot 101 is shaped so that, when the key TR is depressed, the slide 95 will be moved forward where it will be temporarily held by a latch 105 having a lug that engages a notch in the slide.

To start the motor, the control slide 95 has a cam slot 96 (Fig. 2) in which is positioned a stud 97 carried by an arm 98 pivoted at 99 to a stationary frame plate. The cam slot 96 is shaped so that, when the slide 95 is moved forward, the arm 98 will be rocked clockwise. The rear end of arm 98 has a hooked end 102 positioned over a stud 103 carried by an arm 104 forming a part of the bail frame 23 controlling the motor switch 26. When the arm 98 is rocked clockwise by forward movement of control slide 95, its hooked end 102 engages stud 103 and cams the arm 104 counterclockwise to thereby close the motor switch to start the motor. The hooked end 102 moves over the stud and holds the switch closed until the control slide 95 is moved rearward again.

Forward movement of the slide 95 also engages the clutch heretofore mentioned which will now be described. The rear end of the slide 95 is pivotally connected at 106 to the upper end of a lever 107 pivoted at 108 to a stationary frame plate. Pivotally connected to the arm 107 is a pawl 109 urged counterclockwise in Fig. 2 by a spring 109^a. The forward end of the pawl 109 has a shoulder 110 positioned in front of a lug 111 on a latch 111^a pivoted at 111^b and urged counterclockwise in Fig. 1 by a spring 111^c. The lower end of the latch 111^a has a hooked end 111^b normally engaging a shoulder on a clutch controlling member 112 urged counterclockwise in Fig. 2 by a spring 113. The clutch controlling member 112 is operatively connected to a semi-circular connecting dog 115 rotatably mounted in a member 114 (Figs. 2 and 2^a). The connection is such that, when the member 112 is rocked counterclockwise (Fig. 2) by its spring 113, the dog 115 is rotated to engage a notch in the edge of a driving clutch disk 114^a connected to the main shaft 29. The dog together with member 114 is then rotated by the shaft 29 and the member 114, being connected to cam 83, rotates said cam. This clutch and its controls are described and illustrated in more detail in said previously mentioned British Patent No. 450,533. The ar-

angement is such that, when the latch 111^a is released, the clutch is engaged and the cam 83 rotated.

The rotation of the clutch is limited to one revolution no matter what the nature of the depression of the transfer key TR. The stud on the clutch member 114 to which the spring 113 is connected (Fig. 2) is positioned so that, after said clutch has rotated about three-quarters of a revolution, the stud engages the underside of the pawl 109 and raises it to free the lug 111 on latch 111^a. This latch is then moved counterclockwise by its spring 111^c to place its lower hooked end in position to engage the clutch control member 112 as it comes around to its "home" position. As the arm 112 engages the latch 111^a further movement of the clutch causes the dog 115 to be rotated to disengage the clutch. Thus the clutch is automatically disengaged after it has rotated one revolution.

Means is provided for insuring that a complete cycle will occur even though the key TR is released immediately after being depressed. Referring to Fig. 2, when the transfer key TR is depressed, the slide 95 moves forward. The slide is thereupon temporarily latched in position by a pivoted latch 105 urged clockwise (Fig. 2) by spring 105^a, said latch having a lug on it positioned to engage a notch in the slide shown in Fig. 2. The latch holds the slide in its forward position until said latch is released.

Normally the latch 105 is momentarily rocked counterclockwise during the latter portion of the cycle of the drive shaft 29. The shaft 29 carries a clearing cam 85^b operating against a stud 85^c on an arm 85 pivoted at 85^d. The arm 85 is connected to the clearing link 85^a and is urged clockwise by a spring 85^e (Fig. 2). The parts are timed so that the clearing cam acts near the latter part of the cycle of operation to move the link 85^a forward and then return it rearward as described in more detail in said British patent. The clearing link 85^a carries a pass-by pawl 85^f urged clockwise in Fig. 2 by a spring. The latch 105 carries a stud 105^c that is in the path of the nose of the pawl 85^f and against which the pawl normally limits. As the clearing link 85^a is moved forwardly the pawl 85^f passes the stud 105^c but, upon the rearward movement of said link, the pawl engages said stud and momentarily rocks the latch 105 counterclockwise to release the slide 95. The slide is then free to return to normal under the urge of its spring 88^a, which movement releases the key TR.

Provision is also made for preventing the latch 105 from moving back to latching position in the event the key TR is held depressed beyond the time required for the cycle of the parts. For this purpose a second latch 180 is provided pivoted to one of the machine frames and urged clockwise in Fig. 2 by a spring 181. When the slide 95 is in its normal rearward position the stud 182 on said slide to which the spring 88^a is connected holds the latch 180 in the ineffective position of Fig. 2 against the tension of the spring 181. However, when the slide 95 is moved forward by depression of the transfer key TR, the stud 182 moves away from latch 180, whereupon the latch moves to a position such that, when the latch 105 is momentarily rocked counterclockwise during the latter part of the cycle to release slide 95, said latch 105 will be caught and held by the latch 180. This condition obtains until the slide 95 moves rearwardly, whereupon said stud 182 will engage the latch 180 and move it to the Fig. 75

2 position, thereby releasing the latch 105. Additional means is provided to accomplish the same result, making it possible to omit the latch 180 if desired. The lower end of latch 105 carries a stud 105^b positioned to move into an inclined slot in the left-hand end of the arm 109, said left-hand end of the arm also carrying a spring held pawl 109^d having its outer end turned up slightly. At the time the latch 105 is momentarily rocked 10 counterclockwise to release slide 95, arm 109 is in a clockwise position from the position shown in Fig. 2 so that the stud 105^b can move into the slot in the end of said arm 109. The slot is shaped so that the movement of the latch 105 15 raises said arm slightly after which the spring urge on arm 109 and the incline of the slot tends to hold the latch 105 in its released position. This condition obtains until the transfer key TR is released, whereupon the slide 95 moves rearwardly, the arm 107 rocks clockwise, and the arm 109 is moved to the rear to release the latch 105.

A safeguard is provided to prevent the clutch member 114 from overrunning the disk 114^a which rotates counterclockwise as viewed in Fig. 2^a. In normal operations, one of the teeth of the disk 114^a, which is the driving member, engages the underside of the dog 115 to carry the member 114 and the clutch assembly with it. If, however, the member 114 should start running ahead of the disk 114^a it can move only a limited distance relative to said disk before the edge of the semi-circular slot 115^a engages the underside of the next tooth of the disk and prevents any further overrunning.

Provision is made for clearing the rear register and, since it is usually desirable to also clear the front register at the same time, the mechanism that clears the rear register also acts to clear the front register. The motor is caused to operate this mechanism by depression of the clearing key C (Fig. 2) which starts the motor and causes clearing cams to operate as described in detail in said British patents.

Viewing the rear register and associated parts more generally, it will be apparent that a differential mechanism has been provided for operating said register which mechanism is separate and distinct from the differential mechanism governed by the amount keys for entering items in the front register. This second differential mechanism is governed as to its differential positions by stepped members that continuously reflect the amount in the front register. Said differential mechanism is caused to operate at the option of the operator by the depression of the key TR which starts the motor and conditions special driving connections operated thereby so that the special differential mechanism is operated to cause an amount to be entered in the rear register which amount has been indexed by the front register. This cycle of operation of the mechanism by the motor is a separate and distinct operation from the motor driving operations that occur when the amount keys are depressed.

Subtraction

As previously mentioned, subtraction may be performed without requiring that the operator select keys on the keyboard representing the complement of the subtrahend. Instead, he simply enters the subtrahend on the amount keys in the same manner as an add item is entered and then moves a subtract key, whereupon

the machine automatically operates to subtract the item from the rear register.

The manual operations are substantially the same as in performing subtraction on a key-set motor-driven calculating machine in that an item to be subtracted is entered on the amount keys after which a subtract motor bar or key is manipulated to cause the machine to perform a subtraction cycle of operation.

The item entered additively in the front register is subtracted from the rear register by adding the complement of said item into the rear register. By the term "complement of said item" is meant the value $10^n - x$ wherein n is the number of orders in the register into which the entry is made and x is the value of the "said item." For this purpose, each sector 74 is provided with a second set of stepped shoulders 76 (Fig. 1) which is used in performing subtraction. This second set of shoulders 76 is not normally active but provision is made for moving the sectors 74 to render the shoulders 76 active in subtraction. When the shoulders 76 are active, they are adapted to limit the movements of the links 78 in accordance with the complement of the amount standing in the front register. In order that the correct complementary value $10^n - x$ may be entered in the rear register, the shoulders 76 on the units order sector 74 (Fig. 5) are complementary to the shoulders 75 on said sector 74 with reference to the base "10" whereas the shoulders 76 on the sectors 74 (Fig. 4) for all other orders are complementary to the shoulders 75 on said sectors with reference to the base "9." Thus, if the amount "72" entered in the front register is to be subtracted from the rear register, and the sectors 74 are swung to position to render the shoulders 76 active, and the links 78 are moved until stopped by the shoulders 76, the units order link will move 10-2 steps or 8 steps, the tens order link 78 will move 9-7 steps or 2 steps, and all higher order links 78 will move 9 steps.

The subtract key 120 is carried by a lever 119 pivoted at 121. The key top is positioned at an angle so that the operator can very easily place his finger on it and push it rearward. The rearward movement of the subtract key causes a special cycle of certain parts of the machine in much the same manner as when the transfer key TR is depressed.

The subtract lever 119 has a rear extension 122 provided with a cam slot 123 in which is positioned a stud 124 on the bell crank 87 pivoted at 88 and connected to the transfer key TR at 100. The shape of the cam slot 123 is such that, when the subtract lever is rocked clockwise from the position of Fig. 2 to that of Fig. 3, the bell crank 87 is rocked clockwise. This pulls the link 89 forward and releases the bell crank 84 (Fig. 2) so as to place them under the control of the cam 83. The clockwise movement of bell crank 87 also moves the control slide 95 forward where it is temporarily latched by the latch 105. This starts the motor and engages the clutch for rotating the cam 83 through a single revolution during which the bail 81 is moved rearward to permit the differential links 78 to move rearward to differential positions determined by the index members 74.

For changing the position of the index members 74, the subtract lever 119 is provided at its lower end with a cam slot 129 in which is positioned a bail 131 carried by arms 132 pivoted at 132^a to stationary frame plates. The arms 132

are urged counterclockwise by a spring 132^b but normally are prevented from moving by the engagement of the bail 131 with the top of the slot 129 (Fig. 2). The bail 131 is positioned over projections 117 on the links 68 pivoted at 67. As previously described, the links 68 are connected to the levers 64 carrying the studs 62 cooperating with the snail cams 61 on the register pinions 47. Each of the links 68 also has a slot 69 in which is positioned a stud 70 on an arm of the bail 12 of which the corresponding index member 74 is a part. The cam 129 in the lower end of the subtract lever 119 is shaped so that, when subtract lever is rocked clockwise from the position of Fig. 2 to that of Fig. 3, links 68 will be rocked clockwise about the pivot 67. As this occurs the upper ends of the links 68 will be rocked rearward from the position of Fig. 1 to that of Fig. 3. It will be observed that the upper ends of links 68 are much closer to the pivots 73 of members 74 in Fig. 3 than in Fig. 1. The parts are proportioned so that the links 68 slide on the studs 70 at the time the links are rocking, the total result being to swing index members 74 clockwise about their pivots 73 when the subtract key is moved to subtract position. Thus, all the index members 74 which have been differentially positioned in accordance with the amount in the front register, will be swung to new positions corresponding to the "9's" complement of the amount in said register. At the same time, the motor will be started, the clutch engaged, and the differential links 78 moved rearward to cause the actuators 53 to be moved to add this complement into the rear register. It will be understood that, in higher orders of the front register where the pinions are in zero positions, the corresponding links 78 will be conditioned to move nine steps. Thus, the amount in the front register will be subtracted from the rear register by a process of complementary addition.

Near the end of the subtract cycle, the clutch releases the control slide 95 as heretofore explained, whereupon said slide moves forward and, acting on the stud 100, rocks the bell crank 87 counterclockwise to restore the subtract lever 119 and the key 120 to normal.

To provide against rearward movement of the links 78 before the index members 74 have been moved to their new positions by the subtract lever, an interlock has been provided to synchronize these parts. Pivoted to the shaft 121 is a latch 135 (Fig. 3) connected by a weak spring 136 to a projection of the subtract lever 119. The tail of this latch normally rests on a square stud 138 (Fig. 2) on an upward extension of one of the arms 132 that carry the bail 131. The latch 135 also has a shoulder 137 for engagement with the side of stud 138 (Fig. 2). If the subtract lever 119 is rocked clockwise with reasonable rapidity from the position of Fig. 2, the latch 135 will follow it in time to just move its shoulder 137 out of the path of stud 138 so that the movement of the subtract lever can be completed without interference, the arms 132 being rocked clockwise by the movement of said subtract lever. If, however, the subtract lever is moved very suddenly, the weak spring 136 will yield and the shoulder 137 will catch stud 138 which thereby blocks the subtract lever against complete operation. To complete the movement, pressure on the subtract lever must be released and the lever again moved rearward. This interlock prevents the subtract lever being moved so rapidly as to cause the index

bars 78 to be moved rearward before the index members 74 are properly positioned.

The shape of the slot 123 is such that, when the transfer key TR is depressed with the subtract lever in the position of Fig. 2, the stud 124 on bell crank 87 moves into the left-hand horizontal portion of the slot 123 where it locks the subtract lever against operation. Thus, an interlock is provided to prevent the subtract lever from being moved to subtract position while the transfer key TR is depressed.

From the above it will be clear that an operator can either add or subtract items in the rear register at will. If he desires to add an item, he enters it on the amount keys and depresses the transfer key TR which immediately adds the item into the rear register. If he desires to subtract the item, he enters it in the same way but pushes the subtract key 120 rearward, whereupon the item is immediately subtracted in the rear register. In these operations, the front register performs the function of an intermediate or temporary storage register where the item is stored until either the transfer key TR or the subtract lever 119-120 is moved. In both cases the differential index members of the differential mechanism for the rear register is positioned as for ordinary addition but when the subtract lever is moved this indexing is converted or changed to a supplemental indexing. But, insofar as the operator is concerned, he is not interested in the mechanical details of the machine. The thing of interest to him is that it is merely necessary to enter the items and depress the proper key to get either addition or subtraction. These keys are, in effect, an add and a subtract motor bar, the transfer key TR being an add motor bar and the subtract lever 119-120 being the subtract motor bar.

It will be appreciated that the operations required for adding and subtracting in the register are no greater than those ordinarily employed on a key-set machine where a motor bar or a subtract key must be depressed after the item has been entered on the amount keys. In fact, the present machine provides for more efficient action in that the items may be added or subtracted in groups. For example, if there is a series of items to be added, the operator can enter them one after another on the amount keys without depressing any additional key or motor bar and then, after the group has been entered, he can depress the transfer key TR whereupon the sum of the entire group will be transferred to the rear register. Likewise, if he has a series of items to be subtracted, he can enter each subtract item one after the other by simply depressing the amount keys without depressing a motor bar for each operation. After the series has been entered, he moves the subtract lever, whereupon the entire group will be subtracted from the rear register. Thus, the machine enables items to be added or subtracted in groups as distinguished from machines where it is necessary to add and subtract each individual item.

Decimal cut-out

In some uses of the machine, it is not desired to transfer the amounts in the lower orders of the calculator, as, for example, where these orders represent fractions having values below what may be desired in the final result in the rear register. The three lower orders are usually the ones involved and when it is not desired to transfer in these orders, a decimal cut-out or

"full-cent" key is provided which blocks the transfer in the three lower orders. Such a mechanism is disclosed in Henderson 2,063,740 and said mechanism is used in the present machine.

Referring to Fig. 2, the machine has a decimal cut-out or "full-cent" key 140 which, when depressed, prevents the differential links 78 in the three lowest orders from moving out of their normal or "0" positions so that no amounts are entered in these orders in the rear register. The key 140 is carried by a stem 141 (Fig. 6) slidably and rockably mounted on a stud 142 about which it is urged upward and clockwise in Fig. 6 by a spring 143. Near the upper end of the stem 141 is a slot 141a which, when the key is depressed, moves over the edge of one of the keyboard plates under the urge of spring 143 so that the key will be latched in depressed position. Pivoted to a lateral extension of the key stem 141 at 141a is a bell crank arm 144 urged clockwise about its pivot by a spring 146, the clockwise movement of the arm being limited by a stud 148 on the key stem 141 which stud engages a foot 147 of the arm 144. The arm 144 thus moves downward with the key stem but can yield upward against the tension of a spring 146. The arm 144 has a rearward extension 149 positioned over a stud 150 on a bell crank 151 pivoted at 152 and urged clockwise in Fig. 2 by a spring 151a. The lower arm of the bell crank 151 carries a relatively long stud 153 which extends for the width of the first three orders or banks of the machine. Also pivoted on the shaft 152 in each of the three lower orders is a bell crank 154, each bell crank 154 having its lower arm astride the stud 153. The other arm of each bell crank extends forward and the end of this arm has an abutment face for cooperation with a stud 157 on the differential link 78 for its order. The bell cranks 154 are normally above the studs 157 so that the links 78 are free to move but, when the key 140 is depressed, the arm 144 engages the stud 150 and rocks the bell crank 151 counterclockwise against the tension of its spring 151a. As the bell crank 151 is rocked counterclockwise, its stud 153, acting on all three of the bell cranks 154, rocks them to the position of Fig. 6 where the abutment ends of the horizontal arms of said bell cranks 154 are in front of the studs 157 on the links 78 in the three lower orders. It follows that, when the machine is operated to release the links 78 in all orders, those in the first three orders will not move rearward under the urge of their springs, but will be held in their "0" or forward positions and, consequently, nothing will be transferred to the rear register in the three lower orders.

The cut-out remains in effect until the key 140 is released which can be done by pulling it forward so as to disengage the notch 141a from the keyboard plate, whereupon the spring 143 will return the key upward, thereby releasing the bell crank 151 which is rocked clockwise by its spring 151a to return the bell cranks 154 to normal.

When the decimal cut-out is used in connection with subtract operations, it is necessary to make some provision to insure that the subtraction result will be correct. It will be recalled that the shoulders 76 of the stepped index member 74 in the units order are complementary to the shoulders 75 with reference to the base "10" whereas in all other orders the shoulders 76 are complementary to the shoulders 75 with reference to the base "9" to insure the correct result in

subtraction. But, when the decimal cut-out is used, this units order index member 74 is not effective. A correction should then be made in the fourth order of the machine. Provision has been made for effecting this as follows:

Referring to Fig. 7, the differential link 78 in the fourth column, instead of having an integral lug 77 on it, is provided with a slide 160 on its front end having a lug 77^a on it for cooperation with the shoulders 76 in the member 74 in the fourth order. This slide 160 is mounted on two studs 161 carried by the link 78, the slide being urged forward by a spring 166 coiled about the forward stud 161, said spring having a free end engaging a lug 168 on the slide. Normally the slide is prevented from moving rearward by a latch 162 pivoted on the forward stud 161 and having a shoulder 163 engaging the stud 164 on the slide. The latch is urged to a normal latching position by the other free end of the spring 166 which engages a lug 167 on the latch.

When the above-described parts are in the normal position of Fig. 7, the link 78, together with its slide 160 and the lug 77^a, is in condition to act in a normal manner and in the same manner as the other links 78. However, if the slide 160 is released by releasing the latch 162, the link 78 in the fourth order is permitted to move an extra step determined by the length of the slots in slide 160 in which the studs 161 are positioned. This extra step of movement is wanted only in decimal cut-out operations and only when these are subtract operations. Provision is, therefore, made to control the latch 162 by both the decimal cut-out key and the subtract lever.

Pivoted on the shaft 152 is a bell crank 169 (Fig. 7) having its lower arm astride the stud 153 on the bell crank 151. Another arm of bell crank 169 is positioned above the lug 167 on the latch 162 (Fig. 7). When the decimal cut-out key is depressed, as in Fig. 6, the bell crank 151 is rocked from its "A" to its "B" position. The movement of the stud 153 rocks the bell crank 169 but not sufficiently to release the latch 162, the parts being moved to the full-line position of Fig. 7. But, if the subtract lever is also moved to subtract position, the latch will be released by the following mechanism.

Pivoted on the stud 142 (Fig. 6) is a lever 172 having a nose 171 on its upper end and a slot 173 in its lower end positioned astride the bail 131. When the subtract lever is moved to subtract position, the bail 131 is moved from the full-line to the dot-dash position of Fig. 6 through connections heretofore described. As this occurs, the lever 172 is rocked clockwise and its nose engages the stud 150 on the bell crank 151 to rock said bell crank to move the bail or stud 153 from the "B" to the "C" position of Figs. 6 and 7. This rocks the bell crank 169 counterclockwise far enough to cause it to release the latch 162 and, since both the decimal cut-out key and the subtract lever are held in depressed position for the machine operation, it follows that, during the ensuing operation, the differential link 78 in the fourth order can move an extra step so that the subtraction result in the rear register will be correct.

When the link 78 is returned to normal at the end of the cycle, an upward projection 170 (Fig. 7) on the slide 160 engages the stud 152 and arrests said slide while the link 78 continues to move forward. Also, near the end of said cycle, the subtract lever and associated mechanism is

released and returned to normal. This releases the lever 172 (Fig. 6) which is returned to its normal position, and the return of this lever releases the bell crank 151, which is returned to normal by its springs thereby releasing the latch 162.

An interlock is provided to prevent depression of the decimal cut-out key 140 while the subtract key is depressed. Referring to Fig. 6, when 10 the subtract key is depressed, the bail 131 moves from the full-line to the dot-dash position, which rocks the lever 172 clockwise. But if the decimal 15 cut-out key 140 has not been depressed, the stud 150 will not have been engaged by the arm 149 and will not have been moved downward far enough so that it is in the path of the nose 171 of the lever 172. Consequently, lever 172 will not engage said stud but, instead, will move in front of it. If, then, an attempt is made to 20 depress the key 140, the latter cannot move downward to effective position because the stud 150 is blocked by the end of lever 170 and the arm 144—149 cannot move the bell crank 151 counter-clockwise. It would be possible under such 25 conditions to depress the key 140 to stretch the spring 146 but this would not result in conditioning the parts for subtraction. The arrangement is such that the operator is forced to depress the 30 decimal cut-out key first and the subtract key second when he desires to get a subtraction operation with decimal cut-out.

From the above it will be clear that a machine has been provided in which subtraction can be easily performed, either for the full capacity or 35 for the partial capacity of the machine.

I claim:

1. An amount-key-responsive calculator of the class disclosed having a keyboard provided with a plurality of depressible amount keys, a plural order amount differential mechanism, a normally inactive motor driving means for said differential mechanism, an item-receiving registering mechanism at the front of said keyboard, means responsive to the depression of each amount key 40 for starting said motor driving means and causing it to operate the differential mechanism in the order of said key to immediately enter the corresponding digit additively in said item-receiving registering mechanism and to then stop, 45 a "balance" registering mechanism at the rear of said keyboard, mechanical subtraction means extending from front to rear of said machine operable to subtract the amount in said item-receiving from said "balance" registering mechanism, driving connections for said subtraction means operable by said motor driving means, and manipulative means for starting said motor driving means and for conditioning said subtraction means and its driving connections to cause said subtraction means to be operated by 50 said motor driving means through a special cycle independently of said amount differential mechanism, whereby, after an item has been entered on said amount keys, it will be subtracted from 55 said "balance" registering mechanism immediately upon a manipulation of said manipulative means.

2. An amount-key-responsive calculator of the class disclosed having a plurality of depressible 60 amount keys, a plural order amount differential mechanism, motor driving means for said differential mechanism, an item-receiving registering mechanism, means responsive to the depression of each amount key for causing said motor driving means to operate the differential mechanism

in the order of said key to immediately enter the corresponding digit additively in said item-receiving registering mechanism, a "balance" registering mechanism, addition-subtraction means operable to selectively add either the amount in said item-receiving registering mechanism or the complement of said amount to said "balance" registering mechanism, driving connections for said addition-subtraction means operable by said motor driving means, and selectively operable manipulative means for conditioning said addition-subtraction means and its driving connections to cause them to be operated by said motor driving means through a special cycle independently of said amount differential mechanism, whereby, after an item has been entered on said amount keys, it will be added to or subtracted from said "balance" registering mechanism immediately upon operation of said manipulative means and in accordance with the selective operation of said manipulative means.

3. An amount-key-responsive calculator of the class disclosed having a plurality of depressible amount keys, a plural order amount differential mechanism, motor driving means for said differential mechanism, an item-receiving registering mechanism, means responsive to the depression of each amount key for causing said motor driving means to operate the differential mechanism in the order of said key to immediately enter the corresponding digit additively in said item-receiving registering mechanism, a "balance" registering mechanism, a special differential mechanism between said item-receiving and said "balance" registering mechanisms having portions selectively conditionable to transmit either the amount in said item-receiving registering mechanism or the complement of said amount to said "balance" registering mechanism, driving connections for said special differential mechanism operable by said motor driving means, and selectively operable manipulative means for conditioning said special differential mechanism for transmission of said amount or of said complement and for causing said motor

driving connections to operate said special differential mechanism through a cycle independently of said amount differential mechanism, whereby, after an item has been entered on said amount keys, it will be added to or subtracted from said "balance" registering mechanism immediately upon manipulation of said manipulative means and in accordance with the selective operation of said manipulative means.

4. An amount-key-responsive calculator of the class disclosed having a plurality of depressible amount keys, a plural order amount differential mechanism, motor driving means for said differential mechanism, an item-receiving registering mechanism, means responsive to the depression of each amount key for causing said motor driving means to operate the differential mechanism in the order of said key to immediately enter the corresponding digit additively in said item-receiving registering mechanism, a "balance" registering mechanism, a plurality of differential stop elements continuously responsive to the amount in said item-receiving registering mechanism, said stop elements being movable from a position where one set of stops is effective to another position where a complementary set of stops is effective, a set of differential members operatively connected with said balance registering mechanism and movable into engagement with the effective set of stops of said stop elements, driving connections for said differential members operable by said motor driving means, and selectively operable manipulative means for positioning said stop elements and conditioning said driving connections to cause said differential members to be operated by said motor driving means through a special cycle independently of said amount differential mechanism, whereby, after an item has been entered on said amount keys, it will be added to or subtracted from said "balance" registering mechanism immediately upon manipulation of said manipulative means and in accordance with the selective operation of said manipulative means.

WALTER J. PASINSKI.
